United States Patent Office.

GEORGE K. SNOW, OF WATERTOWN, MASSACHUSETTS.

Design No. 3,919, dated March 22, 1870.

DESIGN FOR A PAPER BOX

The Schedule referred to in these Letters Patent and making part of the same.

I, GEORGE K. SNOW, of Watertown, in the State of Massachusetts, have invented and produced a new and original Design for Paper Boxes, of which the following is a specification.

The design consists in giving to a box made of paper or pasteboard the appearance of a trunk.

The design is produced by making the box in the form of a trunk, and printing upon the exterior a representation of handles, straps, buckles, metallic edges, nails, lock-plate, and other accessories and trimmings of a trunk.

The design is represented in the drawing, but from its nature requires further explanation.

The part marked *a*, for instance, representing the lock-plate, is printed in gilt upon the box, and so are the parts marked *b*, representing nail-heads; so also the buckles and rollers *c c*.

The edges of the box, as shown in the drawing, are black, to imitate a trunk bound with iron, but the white lines, necessarily shown at their edges in the drawing, are, of course, unnecessary upon the box itself.

The strips marked *d* are figured, in the drawing, in imitation of wooden guards.

The paper of the box resembles buff leather in color.

I do not, however, wish to limit myself to a box exactly like that represented by the drawing. It is obvious that the gilding may be omitted, and that the box may be of a different color, or even that the box

may vary in shape and proportions and still present the appearance of a trunk.

So, too, the box might be made with a curved top, or with a retreating or projecting front, and come within my invention. And, in like manner, nails might be added or omitted, and the relative position of trimmings might be changed.

The design herein set forth and claimed may, perhaps, be more perfectly understood from a knowledge of the purpose I have had in view in getting it up.

Manufacturers frequently desire a characteristic mark for their goods. When the goods are of such a nature that the mark upon them will not easily be recognized, it is desirable to have a characteristic method of putting them up.

I wish to put up paper collars, manufactured by me, so that packages of my collars can readily be distinguished from those of other manufacturers, and the drawing represents a box such as I intend to use for this purpose.

It is obvious that these boxes may be made in a variety of forms, and suitable for putting up a great variety of articles without losing the characteristic feature of resembling some kind of trunk.

I claim, as a new and original design—

A paper box made to present the appearance of a trunk.
